MOUNTING DEVICE FOR BOILER CASINGS

Ernest C. Witzke, Bayside, N. Y., and Florindo F. Cozza, West Orange, N. J., assignors to Combustion Engineering, Inc., New York, N. Y., a corporation of Delaware

Application April 15, 1952, Serial No. 282,394

5 Claims. (Cl. 122—6)

This invention relates to furnace wall structures and particularly to improved means for interconnecting the exterior casings of furnace walls and the fluid cooled tubes which line the interior of said walls.

This invention is an improvement over the organization of U. S. Patent 2,223,215 issued November 26, 1940 to W. J. Kunz et al. which organization affords practical advantages of a high order but which under certain conditions of commercial operation has, for reasons herein-after explained, presented difficulties that the present invention effectively overcomes.

While the invention is herein described as used in the furnace wall of a steam generator, it is to be understood that it may equally well be used in the walls of other furnaces.

In steam generators of large capacities the combustion rates within the associated furnaces are exceedingly high, thereby developing extremely high temperatures within said furnaces and requiring the interior faces of the furnace walls to be lined with steam generating tubes arranged so that the boiler water circulates therethrough. During operation these furnace wall tubes absorb heat from the fuel burning within the furnace and transmit this heat to the boiler water therewithin causing a portion thereof to be converted to steam. The temperature of the furnace wall tubes is substantially higher than the temperature of the water circulating therethrough, the latter being that of saturated steam at the prevailing pressure under which the steam generator is operating. Said wall tubes are generally backed, outwardly of the furnace, by a refractory and by insulating material outside of said refractory. There is consequently a substantial temperature drop through the furnace wall since the temperature of the outside surface of the insulation is but slightly higher than room temperature.

The wall structure outside of the insulation usually comprises an outer casing made up of a gas tight housing of steel or plastic sheets, which housing is supported and braced by vertical and horizontal stiffening members. This outer wall structure and the inner wall tubes are interconnected by means which maintain the desired spacing therebetween and which serve as a support for portions of the wall. Because of the difference in temperature between the inner wall tubes and the outer casing structure and consequently the difference in expansion therebetween, these spacing means must be capable of accommodating the resulting relative movements of the two members.

It is an object of this invention to provide improved means for spacing an outer furnace wall casing structure from the inner furnace wall tubes, which means will adequately and freely accommodate relative movement therebetween resulting from the differences in thermal expansion.

Other objects of the invention will appear and be brought out more fully in the following description considered in connection with the accompanying drawings, wherein:

2

Figure 1 is a horizontal section through a portion of the wall of a furnace (with the refractory and insulation materials omitted from the right hand portion thereof) taken generally along line 1—1 in Figs. 2 and 3 and showing the furnace wall tubes with the casing structure spaced therefrom by the improved means of this invention;

Figure 2 is a section taken on line 2—2 in Fig. 1 with the refractory material removed;

Figure 3 is a section taken on line 3—3 in Figs. 1 and 2; and

Figure 4 is a section similar to Fig. 1 of another form of the invention.

Referring to the drawings and in particular to Figs. 1, 2 and 3, fluid cooled tubes 1 are shown as vertically disposed along the inner face of a furnace wall generally designated as F. Said tubes are backed, outwardly of the furnace, by a refractory material 2 such as tile or a plastic refractory and by an insulating material 3 outside of said refractory material. A sheet steel casing 4 of generally gas tight construction covers the outside of the insulation 3 and is stiffened by vertical members such as bars 5 and horizontal members such as channels 6 secured thereto; said bars and channels being fastened together to form a rigid support structure.

25 Channel shaped members or guides 7 are fastened to adjacent pairs of the vertically disposed tubes 1 with a flange 8 of said guide being welded longitudinally of one tube in each pair. Web 9 of said channel member or guide 7 has an open ended slot 10 (Fig. 2) that extends 30 parallel to flanges 8 and terminates somewhat inwardly of the top edge thereof. Positioned intermediate said flanges is a plate or shoe 11 arranged to freely slide within said guide 7 in a direction parallel to said flanges and said slot. Said shoe 11 has a slot 12 (Fig. 2) extending transversely of and generally spanning said slot 10. The squared portion 13 of bolt 14 (Fig. 2) fits within slot 12 in a manner to permit free movement of said bolt lengthwise of said slot but to prevent rotation of said bolt within said slot. The head 15 of bolt 14 35 bears against the side of shoe 11 adjacent the tube 1.

Squared portion 13 of said bolt is of sufficient length to extend through the aligned slots 12 and 10 while allowing sufficient clearance, indicated as 16, to permit free movement of guide 7 relative to shoe 11 and angle member 18. The outer end of said bolt 14 is of circular cross section thereby forming a shoulder at the junction with said squared portion and is provided with threads for the reception of nut 19. Said threaded portion snugly fits within a suitable hole in leg 17 of angle member 18 so that upon tightening nut 19 said leg is clamped between said shoulder and said nut thereby rigidly holding bolt 14 in its proper position normal to the surface of leg 17. With this arrangement guide 7 is free to move in both the vertical and lateral direction within the limits 50 permitted by slot 10 and slot 12 respectively.

Furnace wall F is provided with a multiplicity of said angle members 18 which are spaced vertically and arranged normal to the axis of the tubes of said wall. Each adjacent pair of vertically disposed tubes 1, in the organization of Fig. 1, is held in spaced relation to said angle members 18 by means of the guide, shoe and bolt arrangement hereinbefore described whereby the axes of said tubes are maintained in substantial alignment. Clip angles 20 are provided at spaced intervals along each angle member 18 and have one flange fastened to angle members 18 (Fig. 3) as by welding with the other flange being bolted to casing 4 by bolts 21. Thus, angle member 18 is rigidly secured to casing 4 and will accordingly move with said casing.

The embodiment of our invention disclosed in Fig. 4 is similar to that of Figs. 1, 2 and 3 with the exception that in this embodiment vertically disposed tubes 1' are

provided with laterally projecting fins 24 and are therefore spaced apart a considerable distance for the accommodation of said fins necessitating a somewhat different arrangement for fastening the guide to the tubes. Since the spacing of the tubes is too great to economically secure a single guide to adjacent pairs of tubes each individual tube has a guide 8' welded thereto with each guide having a longitudinal slot similar to slot 10 of guide 8 and being operatively associated with shoe 11, bolt 14, angle member 18, clip angle 20 and casing 4 in the same manner as the organization of Figs. 1, 2 and 3.

It will thus be seen that we have provided an arrangement for interconnecting the exterior casing of a furnace with fluid cooled tubes lining the inside wall of the furnace which allows limited vertical and lateral movement of these elements relative to each other and which is extremely rugged in its construction.

In operation of a typical furnace where the walls are suspended from the furnace top (in well known conventional manner) both the casing 4 and the vertically disposed tubes 1 will increase in temperature and expand downwardly as a firing of fuel in the furnace brings the furnace interior from "cold" or room temperature up to "hot" or operating temperature. The increase in the temperature of the tubes 1 will however be much greater than that of the casing 4 causing a downward expansion of the tubes which is considerably greater than the downward expansion of the wall and accordingly resulting in bolt 14 and shoe 11 (secured to casing 4) moving upwardly in slot 10 of guide 7 (secured to tubes 1) while any lateral movement of the tubes relative to casing 4 will be accommodated by horizontal movement of bolt 14 in slot 12 of said shoe 11.

Difficulty has been encountered in the case of prior art devices, typically illustrated by the aforementioned Kunz et al. Patent No. 2,223,215, because of binding of the shoe in the guide due to bending (under certain operating conditions) of the relatively long bolt used in such devices. The organization of our invention completely eliminates this source of difficulty by positioning the mounting for bolt 14 in juxtaposition to guide 7 and by securing the mounting for said bolt to casing 4 in such a manner (via clip angles 20) as to also substantially eliminate the possibility of its bending. With this arrangement an extremely rugged structure is formed which has proved superior to any previously known means for accomplishing the same purpose. The short bolts 14 overcome the difficulty heretofore encountered by the similar use of long bolts in furnace walls; angle iron 18 furnishes a support for the insulating material 3 while serving to maintain definite alignment of the tubes 1 and rigidly supporting bolts 14 in a position normal to the tubes; and rigid fastening of angle members 18 and clips 20 maintains the parallel relation of casing 4 and flange 17 of angle 18 with the tubes 1 and therewith with the web 9 of guide 7.

While we have shown and described preferred embodiments of our new interconnecting means it is to be understood that such disclosure is merely illustrative and not restrictive and that variations and modifications may be made therein without departing from the spirit and scope of the invention. We therefore do not wish to be limited to the precise details set forth but desire to avail ourselves of such changes and alterations as fall within the purview of our invention.

What we claim is:

1. In a furnace wall having fluid cooled tube means arranged on the inner face and a casing on the outer face, spacing means between said tube means and said casing comprising members fastened to said tube means, each member having a slotted portion in a plane parallel to said wall and presenting an outer surface parallel to said wall, a shoe associated with the inner side of said last mentioned portion and being constructed and arranged to slide lengthwise of the slot therein but re-

strained from revolving about an axis normal to the plane of said wall, said shoe having a slot communicating with and extending transverse of the slot in said member, a bolt disposed with its head located on the inner side of said shoe and having a shank extending through both of said slots, said shank being of polygonal section at the head end and reduced to cylindrical section at the outer end thereby providing a shoulder at the junction of said two sections, said polygonal section fitting the slot in said shoe in a manner to prevent rotary motion but permit sliding movement relative thereto and being of slightly greater length than the depth of said two slots, a support member having an angled cross section with one leg thereof parallel to the plane of said wall and bored to receive the said outer end of a plurality of said bolts, a nut threadedly received on the outer end of said bolts for securing said one leg of said support member against said shoulder with the inwardly directed surface of the support member adjacent and parallel to the outer surface of said slotted member, and spaced support means rigidly securing said support member to said casing.

2. In a wall structure including a pair of parallel heat exchange tubes, a channeled member having one longitudinal edge of its flange portions secured to each of said tubes parallel to the axis thereof and provided with an elongated slot in its web portion, said slot being parallel to the axis of said tubes and said web being parallel to the plane containing the axis of said tubes, a shoe slidably mounted in said channel in a manner to restrain rotary motion thereof, said shoe being formed with a slot communicating with and extending transversely of the slot in the web of said channel, a bolt disposed with its head located within said channel and having a shank extending through both of said slots, said shank being of polygonal section at the head end and reduced to cylindrical section at the outer end thereby providing a shoulder at the junction of said two sections, said polygonal section fitting the slot in said shoe in a manner to prevent rotary motion but permit sliding movement relative thereto and being of slightly greater length than the depth of said two slots, a support member having an angled cross section with one leg thereof parallel to the plane of the axis of said tubes and bored to receive said outer end of said bolt, a nut threadedly received on the outer end of said bolt for securing said one leg of said support member against said shoulder, a casing substantially parallel with said tubes and adjacent said support member, and spaced support means rigidly securing said support member to said casing.

3. A wall structure as defined by claim 2 wherein the means for securing the casing to the support member comprise a plurality of spaced members of angled cross section having one leg parallel with and welded to the other leg of said support member and the other leg parallel with and bolted to said casing.

4. In a wall structure including a heat exchange tube, a channeled member having the longitudinal edges of its flange portions secured to said tube parallel to the axis thereof and provided with an elongated slot in its web portion said slot being parallel to the axis of said tube, a shoe slidably mounted in said channel in a manner to restrain rotary motion thereof, said shoe being formed with a slot communicating with and extending transversely of the slot in the web of said channel, a bolt disposed with its head located within said channel and having a shank extending through both of said slots, said shank being of polygonal section at the head end and reduced to cylindrical section at the outer end thereby providing a shoulder at the junction of said two sections, said polygonal section fitting the slot in said shoe in a manner to prevent rotary motion but permit sliding movement relative thereto and being of slightly greater length than the depth of said two slots, a support member having an angled cross section with one leg thereof extending transversely

of the axis of said tube and lying parallel to the surface of said web portion, said leg being bored to receive said outer end of said bolt, a nut threadedly received on the outer end of said bolt for securing said one leg of said support member against said shoulder, a casing adjacent the other leg of said support member, and means rigidly securing said casing to said support member.

5. A wall structure as defined by claim 4 wherein the means for securing the casing to the support member comprise a plurality of spaced members of angled cross section having one leg parallel with and welded to the other

leg of said support member and the other leg parallel with and bolted to said casing.
